RUG AND CARPET TUFTING MACHINE

Walter Loos, New York, N. Y., assignor of one-fourth to Gerda Gjertson, Brooklyn, N. Y.

Application March 23, 1933, Serial No. 662,243

12 Claims. (Cl. 112—79)

This invention relates to new and useful improvements in carpet tufting machines and method of forming carpet tufts.

It is the object of the present invention to provide a machine in which a tufted rug of any desirable size can be completed in a brief operation without the necessity of continuously advancing with respect to one another the needles and the burlap or other textile webbing in which the tufts are formed; in which tufts can be formed without wastage of yarn; in which tufts of any desired length may be formed; and in which any desired color scheme or pattern may be produced as distinguished from prior tufting machines which were capable of producing only striped designs or plain colored carpets.

With these objects in view I provide a tufting machine in which a separate needle is provided for each tuft to be formed so that all the tufts can be made simultaneously and thus the carpet completed in two up and down movements of the needles with respect to the textile webbing. The tufts are formed by hooks or the like which pull straight the yarn formed into loops by the descending and retreating needles, so that it becomes unnecessary to cut the loops after the forming of the tufts, the cutting of the yarn into the desired tuft lengths being performed during one stage of the tuft formation on the needle side of the webbing.

These and other features of the invention will be more fully set forth in the following detailed description of an embodiment thereof which, however, is intended solely to illustrate the invention and not to define its scope for which reference should be had to the appended claims.

In the drawings Fig. 1 is a perspective view of the whole carpet tufting machine with the spool rack;

Fig. 2 is a side elevation of the tufting machine proper showing some of the spools;

Figs. 3 to 6 are sectional views along lines 3—3, 4—4, 5—5 and 6—6 of Fig. 2, respectively, showing details of the yarn feeding mechanism;

Fig. 7 is a sectional view along lines 7—7 of Fig. 2;

Fig. 8 is a sectional view along lines 8—8 of Fig. 2;

Fig. 9 is a sectional view along lines 9—9 of Fig. 8;

Fig. 10 is a sectional view along lines 10—10 of Fig. 9;

Fig. 11 is a back view of the finished carpet;

Fig. 12 is a longitudinal cross-section of the rear or yarn clipped part of the machine shown in Fig. 1;

Fig. 13 is a sectional view along lines 13—13 of Fig. 12;

Figs. 14 to 22 are vertical cross sections of the

tuft-forming needles and hooks in various operating positions; and

Fig. 23 is a vertical cross-section of the finished carpet.

The yarn for the tufts of the carpet is carried on spools 1 rotatably supported in a framework 2 above the tuft-making machine proper. Assuming that the machine is of a size to produce a carpet of the conventional 9 x 12 ft. size, the spools 1 will be wide enough to carry 540 windings of yarn supply and there will be 720 spools in all. In other words, there will be a separate yarn supply for each one of the 388,800 tufts of the carpet. The arrangement of the differently colored yarn supplies will determine the design of the carpet. The spools are rotatable on shafts 3 journaled in the framework 2, a ratchet and pawl arrangement 4 being provided for each spool to permit rotation in one direction only.

From the spools the yarn passes between corrugated rollers 5 and 6 rotatable in opposite directions in end plates 7 of the framework 2. The corrugations of these rollers mesh so as to pull the yarn from the supply spool. There is one pair of corrugated rollers below each spool, the length of the corrugated rollers 5 and 6 being the same as that of the spools. One-half of the corrugated rollers is driven by means of a chain 8, one end of which is fastened at 10 to a vertically movable rail 90 on which the needle bars 9 are resting and the other end of which is connected through a coiled spring 11 with the stationary frame 12 of the tuft-making machine proper at 13. The other half of the rollers 5 is driven by means of a chain 14 mounted in a similar manner. The chains pass over sprocket wheels mounted on the end of each shaft carrying a roller 5 and are kept in position by means of a guide 16. The sprocket 15 drives the roller 5 through the agency of a conventional spring-pressed clutch 17 which rotates the roller 5 step by step in one direction only in response to successive up and down movements of the needle bars 9. The rollers 5 will cause the rotation of the rollers 6 and the step by step unwinding of each yarn from its supply.

The yarn fed out by the rollers 5 and 6 is threaded through the needles 18. A row of 540 needles 18 is supported in a needle bar 9 which is of the same width as the spools 1, there being the same number of needle bars 9 as there are 50 spools, i. e., 720. The plates constituting the needle bars have a keyhole-shaped notch 19 for each needle, the needles themselves consisting of tubes slit open as indicated at 20 almost throughout their lengths, the slits 20 being in alignment with the openings in the keyhole slots 19 at the edges of the needle bars 9. Each yarn is placed within a keyhole slot 19 and the slit 20 in the needle and then threaded through the tubular pointed end 21 of the needle. The yarns are held

- in place by means of spring clips 21' provided above the needle bars, one for each needle. When the needle bar is threaded, a yarn end hangs out of each needle as indicated in Fig. 14.
- When a needle bar and its protruding needles are threaded, the 9-ft. wide needle bar is placed on angle irons 22 carried by cross pieces 23 which may slide on guides 24 in the framework 12 within limits of stops 25 and a jawhead 26. One needle bar after the other is thus set in place and the ends 27 of the needle bars which do not carry any needles (Fig. 8) are held down by means of heavy iron rails 28 extending the full length of the machine.
- When the needle bars are set in place the tubular ends 21 of the needles will project within the perforations in a follower plate 29 hung by means of slidable joints 30 from the needle bars 9. The slidable joints 30 are so arranged that the follower plate 29 will descend with the needle bars 9, but thereafter the needle bars may be moved to a certain distance downward with respect to the follower plate 29. Similarly, when the needle bars rise, they will carry the follower plate 29 with them only during a portion of their travel. The lower surface of the follower plate 29 is roughened to insure firm gripping of yarn ends.
- The next operation is to feed textile webbing 31 between the follower plate 29 and the needle guide 32. The webbing is carried in a supply winding 33 which rotates in a fork 34 of rail 35 of framework 12. From the supply winding 33 the webbing is carried over a pin roller 36 mounted on a bracket 37 of framework 12 and thence over a pair of idlers 38 mounted on a side plate 39 of the framework and an idler 40 mounted by a bracket 41 on the framework. From the idler 40 the webbing 31 is pulled onto an endless belt 42 carried by two rollers 43 and 44 at the two sides of the framework. Pins such as 46 (Fig. 9) project from the endless belt 42 firmly to grip the burlap. The endless belt 42 is driven by means of a gearwheel 47 mounted on the roller 44 and meshing with a gearwheel 48 mounted on a roughened or pinned roller 49 onto which the burlap is led from the roller 44. From the roller 49 the webbing is led onto an endless belt 50 carried by a roller 51 in the side plate 39 of the framework and a roller 52 on a leg 53 of the framework.
- The roller 49, and through the agency of gears 48 and 47, the roller 44 may be rotated by a gear 54 carried on the end of the roller 49 opposite to the one on which gear 48 is mounted (Fig. 7). The gear 54 is engaged by a gear 55 carried by a toothed clutch 56 on shaft 57 driven by motor 58. By pulling out a lever 59 the clutch 56 is caused to engage and supply motive power from shaft 57 for the advancing of the webbing. When the webbing has been pulled clear across the tuft-making machine, the knob 59 is pushed back into its normal position, causing thus the disengagement of clutch 56.
- The tufting operation proper may now commence. The operator pulls out a plunger 60 (Figs. 7 and 8), projecting from the side of the framework 12, against the tension of a spring 61 and thus rocks, through the agency of a rod 62, a rocker arm 63 centrally pivoted at 64 on a bracket 65 carried on a stationary leg 66. A finger 67 carried by the free end of arm 63 is thus moved to the left (Fig. 8) and frees stop 68, whereupon a coiled spring 69 will force the teeth of clutch 70 into engagement. Motive power is now transmitted from a motor 71 through a

worm drive 72 to the main driving shaft 73 which will set the gears and cams, best shown in Figs. 2, 7 and 8, into operation. Gear pairs 74, 75, 76, and 77, through the agency of their associated cam pairs 78, 79, 80 and 81 (all cut alike), will move upward the free ends of bell cranks 82, 83, 84 and 85 (Fig. 2). The bell cranks are pivoted at their centers to the framework by means of brackets 86, 87, 88 and 89, and will draw downward the rail 90 by means of which the cross pieces 23 are interconnected throughout the length of the machine. The cross pieces will glide down on the guide 24 and lower the whole platform made up of the needle bars 9 until the stop 25 is reached.

During the initial stage of this downward movement, the follower plate 29 will press down firmly against the textile web 31, clamping down the projecting yarn ends which have been bent over into the positions shown in Fig. 15 when the web was pulled through the machine.

During the further downward travel of the needle bars 9, the follower plate 29 remains stationary, holding by means of its roughened surface, the ends of the yarn. The needles 18 slowly penetrate through the interstices of the fabric 31 and into holes 91 of the needle guide 32. Through the agency of the chains 8 and 14, the rollers 5 and 6 are operated to feed yarn to the needles, the needles descending into the position shown in Figs. 16 and 17.

During the further revolution of the gears and cams, the needle bars and follower plate will be caused to rise into the position shown in Fig. 18 and at the same time a plate 92 will be lowered through the agency of arms like 93, 94 moved by cams like 95, 96. The cams 95 and 96 are carried on stub shafts 97, 98 driven by gears 99, 100, in mesh with gears 74 to 77. The plate 92 carries bars 101 corresponding in number to the needles 18, and on the ends of each bar a hook 102 is provided. The bars 101 with their hooks 102 are normally within the holes 91 of the needle guide 32, which is stationary on the framework, the ends of the hooks 102 lying within pockets adjacent to but communicating with each hole 91 (see Fig. 14). When the plate 92 travels downward, the hooks will be cammed to the left by the needle guide (Fig. 14) projecting with their ends within the loops of yarn formed upon the rising of the needles 18 (Fig. 18). The cams 95 and 96 are cut to cause a continuation of the downward travel of the hook carrying plate 92, and the hooks will pull down the yarn loops into one branch of a tuft, the formerly clamped yarn ends having been freed by the raised follower plate 29 (Fig. 19).

The shaft 73 has during this time performed less than one-half of its complete revolution. During the continued rotation of the shaft a cam 103 (Figs. 2 and 7) will operate a rocker arm to step, by means of a crank 105 and a spring-pressed pawl 106, a toothed wheel 107. Through the agency of a toothed spring-pressed clutch 108, the pin roller 49 and therefore the pin roller 44 also will be rotated to advance the textile web one step. The length of this step corresponding to the spacing of the needles, is in the present case one-fifth of an inch. The relative positions of the needles and webbing will be illustrated in Fig. 20, i. e., with each needle opposite the hole previously made by the adjacent needle.

During the remainder of the revolution of the main driving shaft, some of the above described operations are substantially repeated. The nee-

5 dle bars and follower plate 29 descend, the needles 18 are pushed through the webbing 31 but now through the holes previously made by the adjacent needles, the follower plate 29 and needle bars 9, as well as the hook holding plate 92, are moved into the positions shown in Fig. 18, causing the hooks 102 to engage the loops formed as shown in Fig. 22. However, from this point 10 on a new operation is performed, i. e., the severing of the yarns at the points indicated in Fig. 22 before the hook holding plate 92 can again descend into the position shown in Fig. 19.

10 This is accomplished by so cutting the cams controlling the rising of the needle bars that 15 upon the last mentioned second elevation of the needle bars they will be moved up into a higher position than shown in Fig. 19 (see Fig. 22), and then before the hook holding plate 92 is lowered 20 into the position shown in Fig. 19, causing a cam 110 (Fig. 7) mounted concentrically with cam 81, to operate through the agency of a rocker bar 111, a bell crank 112 mounted on the frame of the machine, a shaft 113, by means of which a bevelled gear 114 is moved into engagement with 25 a bevelled gear 115 (see Fig. 13). The bevelled gear 115 is driven by motor 58 through the agency of shaft 57, gears 116 and 117 and shaft 113 in one direction and a bevelled gear 132 in the opposite direction. The gear will cause the revolution 30 of shaft 119 on which the bevelled gear 115 is carried, and through a gear 120 mounted on the upper end of shaft 119, a gear 121 will be rotated and cause the revolution of a pinion 122. The pinion engages the teeth of a rack 123 (Figs. 12 35 and 13) in the lower face of a clipping table 124 carrying at its ends a stationary blade 125 and a movable blade 126. Through the pinion and rack arrangement the table 124 is advanced to the left (Fig. 12), whereupon a motor 127 carried by said table is connected in circuit through 40 a shoe 128 contacting with current-carrying rails 129. Through the gearing 130 the motor 127 will cause a chain 131, carried in a groove of the table 124, to vibrate blade 126 from left to right and clip the yarn ends shown at the left-hand end 45 of Fig. 12 at the points indicated at Fig. 22. When the table 124 has advanced the full width of the machine, the cam 110 will pull the shaft 113 to the right (Fig. 13), causing disengagement 50 between gears 114 and 115 and the engagement of bevelled gear 118 with bevelled gear 132 which, through the agency of shaft 133 and gear 134, will rotate the gear 121 in a direction opposite to the one previously described, causing 55 thus the pinion 122 to move through the rack 123, the table 124 back into its normal position indicated in Fig. 12.

60 The cams controlling the hook plate 92 will now operate to move the latter into the position shown in Fig. 19, whereby the hooks 102 will pull through the yarn ends which have been severed and complete the formation of the tufts, as indicated in Fig. 23.

65 As the completion of the main shaft revolution approaches, the pin 68 will ride up on the cam surface 135 formed in the finger 61, opening the clutch 70 against the tension of spring 69 and returning the rod 62 to its normal position. All the gears and cams are now arrested, having 70 returned the needle bars 9, follower 29, and hook holder 92 into the positions shown in Fig. 14. The operator now again actuates the button 59, causing in the previously described manner the advancing through the machine of the textile web which, in the present case, is the completed

carpet, until the full length is pulled through the machine, whereupon the webbing in which the tufts have been formed is severed from the rest of the roll in any suitable manner and the completed carpet subjected to the usual finishing operations.

75 It should be noted that the height of the nap which is formed in the carpet depends on the extent to which the needle bars 9 and follower 29 are raised and upon the positioning of the clipping blades 125, 126, both easily varied and adjusted operations. Therefore, not only is one enabled by the present invention to form in two operations a complete tufted carpet of any predetermined design, but also, without expensive 10 15 alterations, short or long nap carpets may be made to suit requirements.

What is claimed is:

1. In a carpet tufting machine, a plurality of 20 yarn supplies, one for each tuft to be formed, means for holding the free ends of the yarns against the carpet webbing, means for passing each yarn in a loop through the webbing, means for freeing the yarn ends, means for pulling the freed yarn ends through the webbing, means for again passing a yarn loop through the webbing, means for severing the yarn, and means for pulling through the webbing the severed yarn ends.

2. In a carpet tufting machine, a plurality of 30 yarn supplies, one for each tuft to be formed, means for holding the free ends of the yarns against one side of the carpet webbing, means for passing each yarn in a loop through the webbing to the other side, means for freeing the yarn ends, 35 means for pulling the freed yarn ends through the webbing to said other side, means for again passing a yarn loop through the webbing to said other side, means for severing the yarn on said one side, and means for pulling through the webbing the severed yarn ends to said other side.

3. In a carpet tufting machine, a plurality of 40 yarn supplies, one for each tuft to be formed, means for holding the free ends of the yarns against one side of the carpet webbing, means for passing each yarn in a loop through the webbing to the other side, means for freeing the yarn ends, 45 means for pulling the freed yarn ends through the webbing to said other side, means for again passing a yarn loop through the webbing to said other side, means for severing the yarn on said one side, and means for pulling through the webbing the severed yarn ends to said other side.

4. In a carpet tufting machine, needles on one 50 side and hooks on the other side of the carpet webbing, means including said needles for forming yarn loops on said other side of the webbing, means for severing the yarn on said one side of the webbing, and means including said hooks for pulling said loops into straight tufts on said other side of the webbing.

5. In a carpet tufting machine, needles on one 55 side and hooks on the other side of the carpet webbing, means including said needles for forming each yarn into two loops on said other side of the webbing, means for severing the yarn on said one side of the webbing, and means including said hooks for pulling said loops into straight tufts on said other side of the webbing.

6. In a carpet tufting machine, needles on one 60 side and hooks on the other side of the carpet webbing, means including said needles for forming yarn loops on said other side of the webbing, means including said hooks for pulling said loops

- into straight tufts on the other side, means for operating said needles to form the yarn into second loops on said other side, means for severing the yarn on said one side of the webbing, and 5 means including said hooks for pulling said second loops into straight tufts on said other side of the webbing.
7. In a carpet tufting machine, a plurality of yarn supplies, one for each tuft to be formed, a 10 plurality of needles, one for each yarn supply, for passing the yarns through the carpet webbing, a follower plate below said needles having a hole in alignment with each needle, means for moving webbing below said follower, means for lowering 15 the follower to hold against the upper side of the webbing the yarn ends which have been moved with the webbing, means for lowering said needles with said follower and independently of said follower until said needles penetrate through said 20 follower and said webbing, means responsive to the lowering of said needles for drawing yarn from said supplies, a plurality of hooks below the webbing, one for each needle, means operative upon the lowering of said needles for lowering said 25 hooks and raising said follower and needles whereby said hooks are caused to engage yarn loops and draw through the webbing the yarn ends freed by said follower, means operable thereupon to advance said webbing a distance equal the 30 spacing between two needles, means for raising said hooks and lowering the needles and follower, means for again raising said needles, means operative upon the last mentioned raising of the needle bars to sever all said yarns between the webbing and the needles, and means operative thereupon for lowering said hooks to engage the last 35 formed loops and pull through the webbing the severed yarn ends.
8. In a carpet tufting machine, a plurality of 40 yarn supplies, one for each tuft to be formed, a plurality of hollow needles within which the yarns pass, one needle being provided for each yarn supply, a needle bar in which said needles are held, a follower plate below said needles having 45 a hole in alignment with each needle, a needle guide below said follower having holes in alignment with the holes in the follower, a hook within each hole in said needle guide, a plate below said guide carrying said hooks, a supply of carpet 50 webbing, means for moving said webbing between said follower and guide, means for lowering the follower to press said webbing against said guide and hold the yarn ends which have been moved with the webbing, means for lowering said needle 55 bar until said needles penetrate through said follower within the holes in said needle guide, means responsive to the lowering of said needle bar for drawing yarn from said supplies, means operative upon the lowering of said needle bar for lowering the hook holding plate with respect to the needle guide and raising said follower and needle bar whereby said hooks are caused to engage yarn loops hanging within the holes in the 60 guide and draw through the webbing the yarn ends freed by said follower, means operable thereupon to advance said webbing a distance equal the spacing between two 65 needles, means for raising the hook plate and lowering the needle bar and follower, means for again raising said 70 needle bar, means operative upon the last mentioned raising of the needle bar to sever all said yarns between the webbing and the follower, and means operative thereupon for lowering said hooks to engage the last formed loops and pull through the webbing the severed yarn ends.
9. In a carpet tufting machine, a plurality of 5 means for each tuft to be formed, a plurality of hollow needles within which the yarns pass, the needles being longitudinally slotted to facilitate threading and one needle being provided for each yarn supply, a plurality of needle bars in which said needles are held, each bar having keyhole-shaped slots open at 10 the edge of the bar to facilitate threading, a follower plate below said needles having a hole in alignment with each needle and a roughened under surface, a needle guide below said follower having holes in alignment with the holes in the follower, a hook within each hole in said needle guide, a plate below said guide carrying said hooks, a supply of carpet webbing, means including an endless belt for moving said webbing between said follower and guide and holding it 15 taut, means for lowering the follower to press said webbing against said guide and hold with its roughened surface the yarn ends projecting from the needle ends which have been moved with the webbing, means for lowering said needle 20 bars with said follower and independently of said follower until said needles penetrate through said follower within the holes in said needle guide, means responsive to the lowering of said needle bars for drawing yarn from said supplies, means 25 operative upon the lowering of said needle bars for lowering the hook holding plate with respect to the needle guide and raising said follower and needle bars whereby said hooks are caused to engage yarn loops hanging within the holes in the 30 guide and draw through the webbing and within the guide holes the yarn ends freed by said follower, means operable thereupon for actuating said endless belt to advance said webbing 35 a distance equal the spacing between two needles, means for raising the hook plate and lowering the needle bars and follower, means for again raising said needle bars but to a greater height than in the first mentioned instance, a yarn cutter, means operative upon the last mentioned 40 raising of the needle bars for introducing said cutter between the follower and the webbing to sever all said yarns, means for removing said cutter, means operative thereupon for lowering said hooks to engage the last formed loops and pull 45 through the webbing and within the guide holes the severed yarn ends, and means including said endless belt for removing the finished carpet.
10. In a carpet tufting machine, a plurality of 50 rows of needles, one needle for each tuft to be formed, means for twice simultaneously operating all said rows of needles each to form two yarn loops in the carpet webbing, means for advancing between said two operations the webbing a distance equal to the spacing between two 55 needles, and means for forming all said loops into tufts.
11. In a carpet tufting machine, a needle bar having keyhole-shaped notches along one edge, and a hollow needle longitudinally slotted within 60 each notch.
12. In a carpet tufting machine, a needle bar having keyhole-shaped notches along one edge, needles longitudinally slotted with the slots in alignment with the open ends of the notches, and 65 tubular pointed ends for said needles.
